UNITED STATES PATENT OFFICE.

THOMAS J. PYLES, OF COLUMBIA, SOUTH CAROLINA.

RECORDING SYSTEM FOR RAILWAY-SIGNALS.

1,023,037.

Specification of Letters Patent.

Patented Apr. 9, 1912.

Application filed April 7, 1911. Serial No. 619,618.

To all whom it may concern:

Be it known that I, THOMAS J. PYLES, a citizen of the United States, residing at Columbia, in the county of Richland and State 5 of South Carolina, have invented certain new and useful Improvements in Recording Systems for Railway-Signals; and I do hereby declare the following to be a full, clear, and exact description of the invention, 10 such as will enable others skilled in the art to which it appertains to make and use the same.

The present invention relates to a system 15 of railway signaling and apparatus therefor whereby the train despatcher is, in his office, apprised of the execution of such orders as he may communicate to the several train operators within his jurisdiction, as to the display or non-display of the danger 20 signal.

The invention further proposes an arrangement whereby the position of the semaphore signals is told by an audible signal at the despatcher's station, and a permanent 25 record made thereof; and wherein such recording and audible signaling is automatically effected through the actuating of the semaphore operating means.

With these and other objects in view the 30 invention consists in the arrangement and combination of parts hereinafter claimed, and while the invention is not restricted to the exact details shown and described, still for the purpose of disclosure reference is 35 had to the accompanying drawings, in which like reference characters designate the same parts in the several views, and in which:—

Figure 1 is a diagrammatic illustration of the system. Fig. 2 is a longitudinal sectional view partly in elevation, of the recorder and audible signaling apparatus. Fig. 3 is a top plan view of Fig. 2 with the audible signaling device removed and the casing in section. Fig. 4 is a transverse sectional view taken on the line 4—4 of Fig. 3 and looking in the direction of the arrow. Fig. 5 is a detail view in side elevation of the perforating device, and Fig. 6 is a longitudinal sectional view, partly in elevation, 50 of the circuit closure and associated parts.

The plan of the system consists in a train despatcher's station A having electrical connection by the ground and battery wires B and C respectively, with one or more train 55 operators' stations D and at which latter mentioned points are the usual semaphore

signals consisting of poles E and arms F, as shown in Fig. 1.

Located at the train despatcher's station A are a recorder and audible signaling device for indicating to the despatcher the exact position at which the semaphore has been set and to make a permanent record thereof for future reference. Said apparatus is suitably contained within a casing 1 and comprises a movable strip or ribbon 2 wound from a reel or spool 3 to a spool 4 journaled on shafts 3^a and 4^a and passing through a suitable guideway 5. The strip 2 is adapted to have an intermittent movement which is controlled through the semaphore actuating device that closes a circuit through an electro-magnet 6 having a pivotally mounted armature 7, which armature is connected with a bar 8 that moves within a support 9 and carries at one end a pawl 10 engaging with the teeth of a ratchet wheel 11 fixed to rotate with the shaft 4^a of the spool 4 to rotate said spool. A second ratchet wheel 13, also fixed with respect to the shaft 4^a, is engaged by a pawl 14 secured to the casing 1 and holds the spool 4 normally against reverse movement.

From the foregoing it will be seen that when the electro-magnet 6 is energized, the 85 means for which will be presently described, the armature 7 will, when attracted, actuate the bar 8 and effect the rotation of the spool 4 through the medium of the pawl and ratchet engagement (10 and 11) a distance 90 corresponding to the length of one tooth of said ratchet. The strip 2 is adapted to be perforated once each time the electro-magnet 95 is energized and to this end a perforating device is provided comprising an arm 15 having a sharply pointed end 16 and which carries a weight 17. The arm 15 is fixed centrally of a disk 18 which is journaled in the frame 19 and casing 1. (See Fig. 3.) The disk 18 has connected therewith a rod 100 20, which rod also connects with the armature 7.

When the armature 7 is moved through the energizing of the electro-magnet the disk is partially rotated, thus raising the 105 arm 15 to the position shown in dotted lines in Fig. 5, which movement effects the feeding of the ribbon as already explained. The rod 20 is connected to the disk 18 near the center of said disk whereby said disk is rotated to lift the perforating arm from the strip 20 before said strip is advanced. When

the magnet is deenergized the armature 7 is moved to that position shown in Fig. 2 through the agency of the spring 21 and the arm 15 falls through the assistance of the weight 17, when the pointer 16 perforates the strip 2.

The audible signaling device consists in a bell 22 secured to a bracket 23 that is mounted on the casing 1, and a bell striker 24 is 10 pivotally mounted at 25 on said bracket. The striker 24 is provided with a projecting portion 26 that is adapted to be engaged and tripped by a finger 27 on the end of the armature 7. The striker 24 is adapted to 15 be actuated and sound the bell at each forward operation of the armature 7 as will be evident.

The semaphore actuating device consists in the usual chain or rope 28 that passes 20 through a casing 29 secured to the semaphore pole E in any suitable manner. In passing through said casing 29 the rope 28 is wound upon a pulley 30 journaled on the shaft 31 and provided with a disk 32 having 25 a plurality of radially disposed projections or fingers 33. The several fingers 33 are adapted to successively engage and actuate a lever 34 pivotally mounted at 35 on a partition 36 in the casing. The lever 34 is 30 adapted to make and break a circuit through the terminals 37 and 38 of the wires B and C for energizing and deenergizing the electro-magnet 6 as will be understood. The lever 34 is constructed with a hinged joint 35 39, the purpose whereof being to allow the fingers 33 to move in one direction without closing the circuit.

It is proposed that each of the train operator stations be numbered and to this end 40 the disks 32 have the fingers 33 removably mounted so that as many of these fingers may be fitted to the disk to give the same its respective number, thus a station having the number five would have five of these 45 fingers and a station numbered six would have six of these numbered fingers and so on. When the disk 32 is rotated all of the fingers thereof would act upon the circuit closure and close the circuit as many times 50 as there are fingers, since such disk 32 is designed to be completely rotated on each operation of its respective semaphore.

What I claim is:—

1. The combination with a signaling apparatus of a recording apparatus therefor comprising a pair of journaled reels, said reels adapted to have a strip wound thereon; a pivotally mounted arm having perfor-

rating means for said strip; an electro-magnet; an armature for the magnet; a member connecting the armature with one of said reels and adapted to actuate said reel; a member connecting said armature with the perforating arm adjacent the pivotal point thereof and adapted to withdraw said perforating means from the strip before said strip is advanced; and electrical connections between the signaling and recording apparatus, substantially as described. 60 65

2. The combination with a signaling apparatus, of a recording apparatus therefor comprising a casing; a pair of reels journaled in said casing, said reels adapted to have a strip wound thereon; a disk journaled in said casing; an arm mounted on 70 said disk and having perforating means for said strip; an electro-magnet; a ratchet wheel secured to rotate with one of said reels; a bar having a pawl connected with the armature and adapted to actuate the 75 winding reel; a bar connecting the armature and said disk adjacent the center thereof and adapted to withdraw said perforating means from the strip before said strip is advanced; and electrical connections between 80 85 the signaling and recording apparatus, substantially as described.

3. The combination with a railway signaling apparatus, of a recording and announcing apparatus therefor comprising a 90 casing; a pair of reels journaled in said casing; said reels adapted to have a strip wound thereon; a plate intermediate the reels adapted to actuate said strip; a pivotally mounted arm having a pointed end adapted 95 to perforate the strip; an electro-magnet; an armature for the magnet connected with the perforating arm and adapted to actuate the same; a ratchet wheel secured to rotate with the winding reel; a bar having a pawl connected with the armature and adapted to actuate the winding reel; a bar connecting the armature and said perforating arm and adapted to withdraw the pointed end of said arm from the strip before 100 said strip is advanced; a bell mounted on the casing; a pivotally mounted striker for said bell; and a finger on said armature adapted to engage with and actuate said striker, substantially as described. 105 110

In testimony whereof, I affix my signature, in presence of two witnesses.

THOMAS J. PYLES.
